ALARM CLOCK

Richard H. Whitehead, New Haven, Conn., assignor to The New Haven Clock Company, New Haven, Conn., a corporation

Application November 30, 1934, Serial No. 755,294

8 Claims. (Cl. 58—16)

This invention relates to improvements in alarm clocks.

One object of this invention is to provide an improved alarm-sounding construction formed of simple elements readily manufactured and readily assembled to produce an efficient, compact construction at minimum cost.

Another object of this invention is to provide an improved alarm-clock construction in which the bell construction is so formed and located as to provide limit-means for one of the coil-springs of the clock-movement, without the need of employing additional parts.

With the above and other objects in view, this invention includes all improvements over the prior art which are disclosed in this application.

In the accompanying drawing, in which one way of carrying out the invention is shown for illustrative purposes:

20 Fig. 1 is a front elevation of an alarm-clock movement made in accordance with this invention;

Fig. 2 is a horizontal, fragmental, sectional view on line 2—2 of Fig. 1;

25 Fig. 3 is a perspective view of the rear movement-plate, and the bell and hammer-arm construction; and

Fig. 4 is a perspective view of the bell-mounting bracket.

30 In the description and claims, the various parts are identified by specific names for convenience, but they are intended to be as generic in their application as the prior art will permit.

The main portion of the movement construction, including the time-actuating mechanism and much of the alarm-actuating mechanism, are of ordinary construction.

Referring to the drawing, 10 and 11 are the front and rear movement-plates respectively, se-

40 cured together by the four pillars 12. The bell 13 is secured by a rivet 14 or by spot-welding or otherwise to the arm 15 of a mounting or supporting-bracket 16, which latter is connected by rivets 17 or otherwise to the rear movement-plate

45 11. The mainspring winding-arbor 18 is journaled in the movement-plates 10 and 11 and has secured thereto a main-wheel 19, and wound around the arbor 18 is a coiled mainspring 20 of usual type. The bell 13 has its concave face to-
50 ward the main-wheel 19 and mainspring 20, and houses the portion of the latter two parts which extend beyond the edge of the movement-plates 10 and 11. The parts are preferably so proportioned and arranged that when the mainspring 55 20 unwinds to its maximum, it engages against

and is limited by the arm 15 of the supporting-bracket 16. The supporting-bracket 16 and bell 13 together constitute a construction which is hereinafter referred to by the term "bell construction."

The alarm-spring winding-arbor 21 is journaled in the movement-plates 10 and 11 and has secured thereto a coil-spring 22 and alarm-wheel 23, which latter actuates the verge-wheel 24, the rotation of which verge-wheel is controlled by a 10 verge 25 having integral trunnions 26 pivoted in the movement-plates 10 and 11. Firmly secured to or integral with the verge 25 is a hammer-arm 27, the upper end of which is bent to form a shut-off arm 28. The lower end of the hammer-arm 15 27 is given a 90° twist and is formed with a hammer 29, which latter may be integral, and is in a position to have an oscillating action back and forth to strike the edge 30 of the bell 13.

It will thus be seen that by the construction 20 shown and described, the hammer mechanism can be made of maximum simplicity and can strike the bell without extending the hammer out beyond the movement-plates or pillars.

It will also be observed that the arm 15 of the 25 bell-supporting bracket 16 forms a limit or stop for the unwinding of the mainspring, without the need of employing any additional or special construction for this purpose.

The invention may be carried out in other 30 specific ways than that herein set forth without departing from the spirit and essential characteristics of the invention, and the present embodiment is, therefore, to be considered in all respects as illustrative and not restrictive, and all 35 changes coming within the meaning and equivalency range of the appended claims are intended to be embraced therein.

I claim:

1. An alarm-clock construction including: a 40 movement including a pair of spaced-apart movement-plates; a winding-arbor journaled in the movement-plates; a coil-spring not housed in a barrel and surrounding and adapted to be wound by the winding-arbor and adapted to expand beyond an edge of said movement; a bell-construction secured to said movement with the extreme edge surface of the bell adjacent said edge of the movement, the bell-construction being in a position to be engaged by the coil-spring 45 to limit the unwinding of the coil-spring; and a hammer-arm pivoted to the movement and having a hammer adapted to move in a direction approximately perpendicular to the plane of, and 50 55

strike against the extreme edge surface of the bell.

2. An alarm-clock construction including: a movement including a pair of spaced-apart movement-plates; a bell-construction secured to said movement with the edge of the bell adjacent an edge of the movement; and a hammer-arm pivoted to the movement and having a hammer adapted to move in a direction approximately perpendicular to the plane of, and strike against the extreme edge surface of the bell.

3. An alarm-clock construction including: a movement including a pair of spaced-apart movement-plates; a winding-arbor journaled in the movement-plates; a coil-spring not housed in a barrel and surrounding and adapted to be wound by the winding-arbor and adapted to expand beyond an edge of said movement; and a bell-construction secured to said movement with the extreme edge surface of the bell adjacent said edge of the movement, the bell-construction being in a position to be engaged by the coil-spring to limit the unwinding of the coil-spring.

4. An alarm-clock construction including: a movement including a pair of spaced-apart movement-plates; a bell-construction secured to said movement with the extreme edge surface of the bell adjacent an edge of the movement; and a hammer-arm pivoted between the movement-plates and having a hammer adapted to move in a direction approximately perpendicular to the plane of, and strike against the extreme edge surface of the bell.

5. An alarm-clock construction including: a movement including a pair of spaced-apart movement-plates; a bell-construction secured to said movement with the extreme edge surface of the bell adjacent an edge of the movement; and a hammer-arm pivoted to the movement and having a shut-off arm extending transversely of the hammer-arm in one direction, and a hammer extending transversely of the hammer-arm in the opposite direction and adapted to move in a direction approximately perpendicular to the plane

of, and strike against the extreme edge surface of the bell.

6. An alarm-clock construction including: a movement including a pair of spaced-apart movement-plates; a bell-construction secured to said movement with the extreme edge surface of the bell adjacent an edge of the movement; and a hammer-arm pivoted between the movement-plates and having a shut-off arm extending transversely of the hammer-arm in one direction, and a hammer extending transversely of the hammer-arm in the opposite direction and adapted to move in a direction approximately perpendicular to the plane of, and strike against the extreme edge surface of the bell.

7. An alarm-clock construction including: a movement including a pair of spaced-apart movement-plates; a winding-arbor journaled in the movement-plates; a coil-spring not housed in a barrel and between the movement-plates and surrounding and adapted to be wound by the winding-arbor, a portion of the coil-spring being adapted to expand in a direction out beyond an edge of the movement; and a concave bell-construction secured to said movement with the concave side of the bell toward and adapted to house said expandable portion of the coil-spring, said bell-construction being adapted to limit the expansion of said expandable portion of the coil-spring.

8. An alarm-clock construction including: a movement including a pair of spaced-apart movement-plates; a winding-arbor journaled in the movement-plates; a coil-spring not housed in a barrel and between the movement-plates and surrounding and adapted to be wound by the winding-arbor, a portion of the coil-spring being adapted to expand in a direction out beyond an edge of the movement; and a concave bell-construction, including a supporting-bracket, secured to said movement with the concave side of the bell toward and adapted to house said expandable portion of the coil-spring, the supporting-bracket being adapted to limit the expansion of said expandable portion of the coil-spring.

RICHARD H. WHITEHEAD.
